FIG. 2.

UNITED STATES PATENT OFFICE.

WILLIAM H. TIDLAND, OF NICOLLET, MINNESOTA.

GRADING AND DITCHING MACHINE.

SPECIFICATION forming part of Letters Patent No. 518,905, dated April 24, 1894.

Application filed October 31, 1893. Serial No. 489,654. (No model.)

To all whom it may concern:

Be it known that I, WILLIAM H. TIDLAND, a citizen of the United States, residing at Nicollet, in the county of Nicollet and State of Minnesota, have invented a new and useful Grading and Ditching Machine, of which the following is a specification.

My invention relates to improvements in road-making or grading-machines; and has special reference to certain new and useful improvements upon that construction of similar machine illustrated in United States Patent No. 291,427, granted me January 1, 1884.

The objects of my present invention are to provide for a new and improved mode for handling and adjusting the plow; to provide means for raising and lowering the excavating or ditching-wheel; to improve the cups and the mode of securing the same upon the ditching-wheel and operating said cups; to provide for an adjustment of the dumping-wheel, whereby the cups are caused to operate for the purpose of dumping at a desired distance from the plow; and to provide for a raising and lowering of the ditching-wheel whereby the same is thrown into and out of operative position.

With these and certain other minor objects in view the invention consists in certain features of construction hereinafter specified and particularly pointed out in the claims.

Referring to the drawings:—Figure 1 is a perspective view of a machine embodying my improvements. Fig. 2 is a top plan view. Fig. 3 is a transverse vertical sectional view. Fig. 4 is a detail in perspective of a portion of the rim of the ditching-wheel together with some of the cups.

Like numerals of reference indicate like parts in all the figures of the drawings.

In the practice of my invention I employ a substantially semicircular frame 1, which at one side or at its ends is connected by the longitudinal frame-bars 2, which in turn are 45 suitably braced at points desired. In front and rear bearings between the beams 2 I swivel front and rear caster-wheels 3. In the beams 2 I also locate a pair of transversely disposed cranked-shaped rock-shafts 4, connecting said shafts by means of a pair of plow-beams 5. To the lower ends of these plow-beams I secure an ordinary side-plow

6, whose moldboard is toward the interior of the framework. It will be obvious that through the medium of the lever 7 which is 55 pivoted at the inner side of the inner beam 2, the said plow-beams may be raised and lowered, and by reason of the fact that they are connected to two similarly cranked rock-shafts, the bottom of the plow, that is the 50 point and heel, will also be on the same level whether the plow be elevated out of operative position or lowered into operative position. Any means may be employed for giving motion to the plow, and in the present instance, 65 as seen, I pivot the lever 7 to a locking standard 8 providing said lever with a locking-pawl 9 for engaging the standard.

At the front of the beams 2 I locate a seat-standard 10, which supports a seat 11 for the 70 accommodation of the driver, it being understood that the draft-mechanism is applied at the front end of the machine, as shown. In rear of the plow, or rather immediately above the same, I locate a second standard 12 which supports a seat 13 for the accommodation of the operator who is positioned at this point for the purpose of manipulating the levers and other devices of adjustment heretofore and hereinafter described.

80 The opposite side of the semicircular frame 1 is provided with a cross-bar 14, and the same, together with the frame 1, accommodates a transverse axle 15, upon which is mounted for rotation a ground-wheel 16. A 85 standard 17 rises from the front side of the frame 1 and terminates in an eye, and at the rear side of the frame 1 a pair of standards 18 rise and accommodate a winding-shaft 19, at whose inner end or adjacent to the seat 13, 90 there is located a lever 20 or other winding-device by which means the shaft 19 may be oscillated. A chain 21 is wound upon the shaft 19, and at its free end is secured at the rear end of the frame 22. An oblong frame 95 22 is located in the semicircular frame 1, and at its front end is provided with an eye 23 which engages with the eye at the upper end of the standard 17. The rear end of the frame 22 is also provided with an eye, and in the 100 same is coupled the lower end of the chain 21. By means of the eye 23 being coupled with the standard 17, it will be seen that the rear end of the frame 22 is capable of raising and

lowering, which raising and lowering I accomplish through the medium of the lever 20 operating the shaft 19 to wind the chain thereon or pay the same therefrom. The frame 22 is held a proper distance from the plow by the bar 22^a, pivoted to the frames 22 and 1, as at 22^b. Opposite bearings are arranged in the upper and lower sides of the frame 22, and in the same is mounted for loose rotation an inclined shaft 24. This shaft 24 serves as the axis of the ditching-wheel 25, which as shown, is a large wheel located in the frame 1 and extending from the outer edge thereof to a point adjacent to the moldboard side of the plow. The rim 26 of the wheel 25 is provided at intervals with bearing-eyes 27, and passing through the same is a rod 28. This rod 28 forms a bearing for a series of longitudinally curved, hinged or pivoted dirt conveying cups 29, which radiate toward the center of the wheel and normally lie upon the same. Each of these cups is provided at its inner end with an eye 30, and passing through the eyes of the series is a loose slat connecting chain or belt 31, whereby the entire series of cups is connected. The bottom of the wheel, it will be seen, travels upon the ground-wheel 16 at one side and being inclined, as shown, at its opposite side or that side adjacent to the plow, travels upon the ground, so that as the machine is drawn along the wheel 25 is revolved by reason of its contact with the ground and the said wheel 16.

35 A curved track 32 extends from the rear end of the frame 22 concentric with the shaft 24 thereof to a point near the front end of the frame 22, and then abruptly bends outward and downward forming a standard 33, 40 whose lower end is fastened to the semicircular frame 1. A swinging-arm 34 is pivoted at its inner end to the upper end of the shaft 24, and at its outer end is bifurcated, as at 35, and accommodates a vertical pin or journal 36 upon which the dumping-wheel or disk 37 is mounted. A yoke 38 of U-shape has its terminals connected with the track 32, passes under the dumping-wheel 37, and forms a lower additional bearing for the journal-pin 45 36. This yoke is designed to travel upon the track 32 and aid in supporting the arm 34 upon the track. The arm is also provided with an eye 39 upon its upper side, which loosely engages with the track 32. By this means the dumping-wheel is located and supported above the periphery of the wheel 25 and slightly inside the same, and inasmuch as the series of connected cups pass over the wheel 37, it will be seen that each is successively brought to a vertical position, to dump its contents upon the ground at such a point as may be regulated by the position of the wheel 37.

In order to provide for a convenient adjustment of the wheel 37 I connect with the journal-pin thereof a curved rod 40, which terminates at one end in a handle 41, and

passes through a guide-eye 42 formed in a guide-standard 43 which rises from the frame 22, the handle being in easy reach of the operator when mounted upon the seat 13. A pair of hangers 44 depend from the upper frame-bar of the frame 22 at the upper end of the same, and in the lower ends thereof is journaled a depressing-wheel 45 which travels over the series of cups, depressing them upon the wheel 25 as they leave the dumping-wheel 37, whereby they are forced back positively to their refilling positions. This completes the improvements upon my former construction, and it will be seen that I provide, as before stated as being the objects of my invention, first, a convenient means for raising and lowering the plow; second, a convenient means for raising and lowering the ditching-wheel; third, a convenient means of attaching the cups to the ditching-wheel; fourth, means for adjusting the dumping-wheel, whereby the latter is caused to dump the dirt at a desired distance from the plow which is forming the ditch; and, finally, I provide for a depression of the cups after the same have dumped and are about to be refilled.

The operation of the machine, it will be understood, is similar to that described in the previous patent heretofore referred to and may be briefly stated as follows:—The machine is drawn along with the plow at the side of the road, said plow forming a ditch, as will be obvious, and the soil turned up by the moldboard of the plow is deposited upon the cups as they are successively brought adjacent to the plow. These cups are carried by the wheel 25 and are successively operated upon by the dumping-wheel, or in other words, are elevated and their contents discharged from the machine at any point of the road, the point being varied in accordance with the width of the road and the desired convexity of the road-bed in a manner obvious.

I do not limit my invention to the precise details of construction herein shown and described, but hold that I may vary the same to any degree and extent within the knowledge of the skilled mechanic.

Having described my invention, what I claim is—

1. In a road making machine, the combination of a framework, a plow arranged at the inner side of the framework, a ditching wheel inclined and arranged in the framework at the side of the plow and provided with a series of flexibly connected dirt conveying cups hinged at their lower ends to the wheel, and a dumping wheel arranged at one side of the ditching wheel and engaging the inner faces of the cups, whereby the latter are swung outward for dumping, substantially as described.

2. In a road-making machine, the combination with a semicircular frame, longitudinal connecting-beams at the ends thereof, a revolving inclined ditching-wheel supported

- within the semicircular frame and provided with hinged cups, and means for raising and lowering the cups, of a pair of crank-shafts arranged in the beams, a pair of plow-beams carried by the crank-shafts and connecting the same, a plow at the lower ends of the beams, a lever connected with the crank-shafts and provided with locking-devices, substantially as specified.
- 5 3. In a road-making machine, the combination with a framework, and a plow at the inner side thereof, of a frame loosely suspended in the framework at the side of the plow, means for raising and lowering the frame, a 15 ditching-wheel carried by the frame, ditching-cups arranged upon the wheel, and means for raising the ditching-cups for the purpose of dumping the same, substantially as specified.
- 10 4. In a road-making machine, the combination with a frame, a plow at the inner side thereof, a front standard, a pair of rear standards, a rock-shaft arranged in the rear standards, a lever for operating the rock-shaft, and 25 a chain wound upon said shaft, of an oblong frame having an eye at its front end loosely connected with the eye of the front standard and loosely coupled at its rear end to the free end of the chain, an inclined shaft arranged 30 in the frame, a ditching-wheel arranged upon the shaft, a series of cups hinged upon the wheel, means for rotating said wheel, and means for elevating the cups, substantially as specified.
- 35 5. In a road-making machine, the combination with a framework, and a plow at one side thereof, of an inclined ditching-wheel supported at the side of the plow, means for rotating said wheel, a series of curved ditching- 40 cups hinged at their outer ends to the rim of the wheel, a slack connection between the inner ends of the cups, and a dumping-wheel over which such connection travels arranged above the ditching-wheel, substantially as specified.
- 45 6. In a road-making machine, the combination with a framework, and a plow at one side thereof, of an inclined ditching-wheel supported at the side of the plow, means for rotating said wheel, a series of curved ditching-cups hinged at their outer ends to the rim of the wheel, a slack connection between the inner ends of the cups, a dumping-wheel over which such connection travels arranged above the 50 ditching-wheel, and means for adjusting the dumping-wheel, substantially as specified.
7. In a road-making machine, the combination with the framework, the plow at the inner side thereof, the oblong frame arranged within the framework and having a central axis, means for supporting said oblong frame, of a ditching-wheel arranged upon the axis, a series of cups hinged at their outer ends to the rim of the wheel, a slack connection between the inner ends of the cups, a curved 60 guide above the ditching-wheel, an arm carried by the axis and arranged for movement at its outer end upon the guide, a dumping-wheel having its axis journaled in the outer end of the arm in the path of the cups, and a 65 lever for swinging said arm, substantially as specified.
8. In a road-making machine, the combination with the framework, the plow at the inner side thereof, the oblong frame arranged 70 in the framework, the inclined axis arranged in the frame, the ditching-wheel arranged upon the inclined axis at the moldboard side of the plow, a series of cups hinged at their outer ends to the rim of the ditching-wheel, 75 and a slack connection between the inner ends of the cups, of a superimposed curved guide-bar, a yoke-bar of U-shape having its ends loosely mounted on the guide-bar, a swinging arm connected to the upper end of the axis and at its outer end bifurcated and having an eye for engaging the guide-bar, a dumping-wheel having its axis arranged in the bifurcated ends of the arm and in the yoke, a guide-eye arranged upon the frame, 80 and a curved lever pivoted at its outer end to the axis of the dumping-wheel and at its inner end terminating in a handle and passed through the guide-eye, substantially as specified.
9. In a road-making machine, the combination with the framework, the plow, and the revolving dumping-wheel, of a series of bearing eyes arranged upon the rim of the wheel, a bearing-rod passed through the eyes, a series of curved cups hinged upon the rod and having eyes at their inner ends, a chain connecting the eyes, and a dumping-wheel arranged in the path of the chain, substantially as specified.
- 95 In testimony that I claim the foregoing as my own I have hereto affixed my signature in the presence of two witnesses.
